UNITED STATES PATENT OFFICE.

WILLIAM D. ARNETT, OF PARMA, IDAHO.

DESIGN FOR A KNIFE.

SPECIFICATION forming part of Design No. 31,965, dated December 12, 1899.

Application filed November 15, 1899. Serial No. 737,133. Term of patent 14 years.

To all whom it may concern:

Be it known that I, WILLIAM D. ARNETT, a citizen of the United States, residing at Parma, in the county of Canyon and State of Idaho, have invented and produced a new and original Design for Knives, of which the following is a specification.

My invention relates to a new and original design for knives; and the leading feature 10 consists in the peculiar shape or configuration given to the same.

In the accompanying drawings, Figure 1 represents a perspective view of a knife constructed according to my invention. Fig. 2 15 is a cross-section on line *xx*.

In the said drawings the reference-numeral 1 designates the handle of the knife, and 2 the blade.

The numeral 3 designates the back of the 20 blade, 4 the point, and 5 the cutting edge.

This cutting edge from the junction with the handle is curved or rounded for a short distance and is then extended in an approximately straight line to the point which is rounded. At the back of the knife near the 25 point is formed an upwardly-bent rounded or curved extension or projection 6. It will be noted that the blade is at an angle to the handle.

Having thus described my invention, what 30 I claim is—

The design for a knife, substantially as herein shown and described.

In testimony whereof I have hereunto set my hand in presence of two subscribing witnesses.

WILLIAM D. ARNETT.

Witnesses:

E. E. DUTTON,
FRANK J. SMITH.
